PIERRE AUGUSTE DANIEL MARTI, OF MONTBELIARD, AND CHARLES FREDERIC MARIE BERTIN AND ALBERT EMILE GUSTAVE NANDILLON, OF TOULON, FRANCE

EMITTING OR RECEIVING VIBRATION DEVICE FOR SUBMARINE SOUNDING

Application filed September 30, 1931, Serial No. 566,134, and in France October 8, 1930.

The proceeding of ascertaining the depth of the sea is known in which the depth is deduced from the time elapsed between the emission of a sonorous or ultrasonorous wave 5 set up on board of the ship and the return of this wave to the ship after having undergone reflection at the bed of the sea.

In certain apparatuses, in order to set up the vibrations, an acoustic member in contact 10 with the sea water is struck with a hard body, say a hammer, in other apparatuses an excitation of suitable kind generates mechanical vibrations in an acoustic radiator in contact with the sea water, (for instance, in the 15 soundings by means of piezo-electric quartz).

A microphone is generally used for the reception, sometimes also the same device is used as well for the emission as for the reception when this device is a convertible one.

20 When it is impossible to mingle together or to place in juxtaposition the emitter and the receiver, they are generally settled very close to each other in order that the device be adapted to ascertain the depths precisely 25 enough even when said depths are shallow ones (say a few fathoms).

It has been proposed, for the purpose of avoiding piercing the hull of the ship, to put the generating or receiving vibration device 30 inside a chamber filled with water and constituted by a bottom-less box riveted on the inner side of the hull. Such an arrangement is subject to many drawbacks. In particular:

35 The vibrations are transmitted directly between the hull and the part of the chamber wall which constitutes or sustains the vibrating surface, and this, even if a fluid tight joint, say an elastic pad some ten mils thick 40 is interposed between the flange of the chamber and the hull. Because of that, during the emission, a great part of the energy is wasted in the hull and thus lost for the signal, and the same vibrations, so dispelled in the hull, 45 actuate too strongly the receiver which is placed, as said above, relatively near the emitter; during the reception, the vibrations created inside the walls of the hull by the sailing of the ship and by its inner life, are 50 strongly transmitted to the vibrating surface

of the receiver and disturb the reception of the always very weak echo.

The sheet plates of the chamber, rather thin (between $\frac{1}{4}$ and $\frac{1}{2}$ inch thick), are sensible to the received or emitted vibrations 55 and so engross a part of the emitted or received energy.

The height of the chambers has generally a rather large value (about twenty inches) relatively to the sonorous wave lengths used (which are about 20 inches for the sounds and two inches for the ultrasounds), consequently while receiving or emitting, inside the liquid filling the chamber arise acoustic resonance phenomena similar to those produced in an organ pipe, and said phenomena have for their effect to waste the acoustic energy and to lengthen the sonorous phenomena. This lengthening is specially harmful 60 when sounding in shallow waters because the receiver, always more or less actuated by the emission, must then be brought back to stillness in a very short time before being reached by the echo.

65 The chamber flange must be curved exactly 70 like the hull. Therefore it is impossible to create standard apparatuses appropriated for every ship.

The invention has for its object a chamber 75 for emitting or receiving sounding apparatus 80 avoiding all the above drawbacks.

The principal feature is the following one: Between the hull and the part of the chamber wall which constitutes or sustains the vibrating surface is laid a device preventing the vibrations to be transmitted from the one to 85 the other.

Said device shall be preferably constituted as follows: A deformable member, say a thick ring of soft india rubber shall be interposed between the lower edge of the chamber walls and the hull, the breadth of said ring and its height between the edge and the hull being comparable in greatness (say one inch as well for the one as for the other) in order 90 to be easily put out of shape by crushing. Because of its deformability, this ring will withstand the passage of the vibrations from the chamber to the hull or vice versa, and further, it will afford the fluid tightness of 95 100

the chamber provided that said chamber is applied against the hull by a sufficient pressure. Therefore it shall no more be necessary that the lower edge of the chamber have the same form as the hull, it should even be possible to use a standard chamber the lower edge of which should be plane, and which should suit to every ship. Moreover the chamber shall be fastened on the hull by binding means preventing the transmission of vibrations in order to avoid relapsing into the above indicated drawbacks, for instance by means of stems of adjustable length fulcrumed by one end on the frame work of the ship and by the other end on an other thick ring of soft india rubber shaped as the former one and lying on the upper side of the chamber.

Further the part of the chamber between the deformable joint and the vibrating surface shall be heavy enough to remain substantially insensible to the vibrations, for instance the chamber shall be constituted by a cast iron cylinder about two hundred pounds weight with walls about four inches thick; lastly the height of the chamber shall be small enough in reference with the wave length used to avoid any resonance phenomena inside the liquid filling said chamber; say it shall be only one fifth of the employed wave length or about four inches for an apparatus using a sound of audible frequency and one half of an inch for an apparatus using ultra audible frequencies.

By way of example we have below disclosed and represented in cross section on the annexed Figures 1 and 2 two forms of execution of said chamber which can both be used for emission as well as for transmission.

As represented on Fig. 1 the chamber is constituted by a big cast iron bottomless cylinder 1. This cylinder sustains the vibrating surface which shall be constituted by a rigid slab borne by a ring shaped and thinner zone 2'.

A soft india rubber ring 3 is partly fitted in the lower plane edge of the cylinder 1 and bears on the hull of the ship. The inside of the chamber has the small height as indicated above and is filled with a liquid, generally water, by the pipe 5. In 4 is represented a transmission device, say for the emission a hammer which striking on the vibrating surface shall start its free vibrations, or a receiving device as a microphone which shall detect the vibrations of 2 produced by the echo. The chamber is pressed against the hull by two stems each in two parts 11, 11' and 12, 12' with screwed ends the lengths of which can be adjusted by coupling boxes 11' 12'', said stems are fulcrumed against the ship frame 13 by one end and by the other against a flange 15 lying on a soft india rubber ring 14 fitted in the upper face of the cylinder 1.

In the device represented by Fig. 2 the top of the cylinder 1 is constituted by a thick slab strongly fastened on the cylinder 1, the acoustic emitter or receiver 9 is inside the chamber 7 and sustained by a holder 10.

Owing to said construction the direct transmission of the vibrations between the vibrating surface 2 or 9 and the hull 6 is prevented by the damping india rubber ring 3. The damping india rubber ring 14 prevents in the same way the vibrations to be transmitted between the vibrating surface 2 or 9 and the ship frame by intermediary of the stems 11, 12. Moreover the mass of the chamber is such that it is substantially insensible to the vibrations. The small height of the same chamber hinders the resonance phenomena inside the liquid filling it. Notwithstanding the lower edge of the chamber is plane shaped the device can be used on every ship without having to take in consideration the curvature of the hull which is moreover always small in the parts where the apparatus is placed.

What we claim is:

1. In a device for submarine sounding on board of a ship by means of vibrations reflected from the bottom of the sea, comprising a chamber opened on one face, said face bearing against the ship's hull below the water line, a liquid filling said chamber, a vibrating wall on said chamber and in contact with the said liquid, means for fluid tightly insulating the hull from the walls of the said chamber, said means being resilient and damping, attaching means comprising resilient damping devices between the ship and the chamber, both insulating and attaching means being arranged so as to prevent the vibrations to be transmitted to the vibrating surface otherwise than through the liquid.

2. In a device for submarine sounding according to claim 1, wherein the thickness of the walls of the liquid containing chamber is so designated that the said walls are not sensible to the vibrations of the liquid in the said chamber.

3. In a device for submarine sounding according to claim 1, wherein the height of the liquid containing chamber is small with respect to the wave length, in the liquid of the chamber, of the vibrations to be transmitted.

4. In a device for submarine sounding according to claim 1, wherein the thickness of the walls of the liquid containing chamber are substantially equal to their height.

5. In a device for submarine sounding according to claim 1, wherein the height of the liquid containing chamber is substantially one fifth of the wave length, in the liquid of the chamber, of the vibrations to be transmitted.

6. In a device for submarine sounding according to claim 1, located against a curved

ship's hull, wherein the edges of the open face of the liquid containing chamber are in a plane, and wherein the resilient fluid tightening means disposed between said hull and said edges of the chamber include a thick ring body of india rubber, fitted in part in the said edges of the chamber and having its width substantially equal to its free height, and the attaching means comprising a thick 5 ring body of india rubber fitted in part in the top edges of the said chamber and having its width substantially equal to its free height, and adjustable stems fulcrumed at one end 10 to the ship frame above the said chamber and at the other end bearing upon the top india rubber ring.

7. In a device for submarine sounding according to claim 1, wherein the liquid containing chamber comprises a cast iron cylinder limited by two transverse cross-sections, the top end being closed, said cylinder being 20 two hundred pounds weight, its external diameter being sixteen inches wide, its lateral walls four inches wide and high.

8. In a device for submarine sounding according to claim 1, wherein the top wall of the liquid containing chamber is in the form of a thick slab, of which a portion of reduced thickness is adapted to connect said slab to the lateral wall of the said chamber.

In testimony whereof we affix our signatures.

CHARLES FREDERIC MARIE BERTIN.
